CLAIM

(21) Appl. No.: **29/344,732**

The ornamental design for a navigation device and mount for navigation device for use on a handgrip of a vehicle, as shown and described.

(22) Filed: **Oct. 2, 2009**

DESCRIPTION

(51) **LOC (9) Cl. 10-04**

FIG. 1 is a perspective view of a navigation device and mount for navigation device for use on a handgrip of a vehicle showing our new design;

(52) **U.S. Cl. D10/65; D10/98**

FIG. 2 is a right side view thereof;

(58) **Field of Classification Search** D10/65,

FIG. 3 is a left side view thereof;

D10/98; D14/341, 344, 507, 138 R, 138 AA,

FIG. 4 is a front view thereof;

D14/203.3, 203.4, 203.5, 203.7; 342/386,

FIG. 5 is a rear view thereof;

342/351, 419, 457, 357.06–357.13, 20; 343/702,

FIG. 6 is a top view thereof; and,

343/711, 712, 713, 714; 345/87, 104, 133,

FIG. 7 is a bottom view thereof.

345/156, 168, 173, 901–905; 348/180, 184,

The broken lines shown in the drawings are for illustrative purposes only and from no part of the claimed design.

348/315, 739; 364/444, 499; 701/206–209,

701/213, 214; 248/276.1; 73/490, 493, 514.39,

73/527; 235/95 R; 324/160–180, 207.13,

324/207.22, 207.25; 340/432; 702/145–148

See application file for complete search history.
